WILLIAM J. PRESS, OF OTTAWA, ONTARIO, CANADA

FLUID PUMP

Application filed January 15, 1927. Serial No. 161,350.

The present invention has relation to improvements in a fluid pump appertaining particularly to one of that character embodying a rotor and a stator casing, in which 5 the rotor is eccentrically mounted, having inlet and discharge ports for the fluid.

An object is to provide a pump of this nature with a rotor having propelling vanes and fluid receiving pockets about its periphery.

A further object is to provide a pump as described with a rotor having peripheral fluid carrying pockets so configurated as to permit of the insertion of the propelling 15 vanes which being thus interchangeable may be advanced from their normal pockets to the fluid pockets when the original vane accommodating pockets become worn thus doubling the length of time that the rotor 20 can function satisfactorily, the vacated normal vane accommodating pockets serving then as fluid carrying pockets.

A further object is to provide a fluid 25 pump wherein the stator casing encloses an annular liner sweated in place having perforations to register with both the inlet and outlet ports, the vanes of the eccentrically mounted rotor being reciprocally mounted in longitudinally extending radial 30 pockets therein and spring urged into continual contact with the liner.

A still further object is the provision of a fluid pump capable of starting more rapidly 35 and characterized by augmented efficiency, durability, quietness and smoothness of operation and simplicity of design and construction all of which contribute to the production of a device that is of commercial worth.

To the accomplishment of these and related objects that may appear, as the description proceeds the invention resides in the construction, combination and arrangement of the several co-operating parts as 45 shall be hereinafter more fully described, illustrated in the accompanying drawings and pointed out in the claims hereunto appended.

The invention can be most clearly described and will be best understood when 50 reference is had to the accompanying draw-

ings, forming a part of this disclosure and wherein like characters indicate like parts throughout the several views.

In the drawings:—

Fig. 1 is a side elevation of the device; 55

Fig. 2 is an end elevation thereof;

Fig. 3 is a vertical section on the line 3—3 of Fig. 2;

Fig. 4 is a section at right angles thereto as on the line 4—4 of Fig. 1; and 60

Fig. 5 is a detail of the metal liner.

The present embodiment of the invention has been particularly designed for use in mixing and feeding fuel to an oil burning furnace, both oil and air entering by the 65 inlet port and an atomized blast of gaseous fuel being blown from the outlet.

The stator casing 6 having a removable side plate 7 includes an open inlet pipe 8 and an outlet pipe 9, the former of which 70 receives a small oil feed pipe 10 that enters it radially. A metal liner 11 in the form on an annular bushing ring is sweated into the casing 6 and perforated opposite the opening of the inlet and outlet pipes 8 and 9 75 respectively, as at 12, thus giving continuity to the inner circumference of the casing and tending to break up or atomize the fuel both entering and leaving. A rotor 13, carried by an eccentrically positioned drive 80 shaft 14, has a plurality of deep longitudinally extending radial grooves or pockets 15 in which radially reciprocable vanes 16 are mounted. The bases of these pockets are recessed as at 17 and the registering parts 85 of the inner ends of the vanes correspondingly recessed as at 18 to accommodate therebetween compressed coil springs 19 that act to urge the vanes 16 into continual contact with the lining ring 11. 90

Between each adjacent pair of vanes, the rotor 13 is provided with a fuel pocket or reservoir 20 intended to carry a quantity of the fuel when above the horizontal plane of the rotor axis thus maintaining at all 95 times a reserve supply of fuel for instant starting and contributing in a material and decided way to more adequately supply the outlet and adding to the conservation of fuel when starting.

In the illustrated form of my pump the oil pockets 20 are shown as similar to the vane accommodating pockets 15, the advantage thus gained being that the vanes 16, when their original pockets become worn due to the constant turning of the rotor in one direction with the accompanying rubbing of the vanes against the same side wall of the pockets, can be advanced to the fluid carrying pockets when the original vane accommodating pockets become the fluid carrying pockets or reservoirs whose worn condition does not impair or lessen their utility as such.

As the structural details of my invention have been thoroughly described, there now follows a brief reference to its use and operation.

On the starting of the rotor 13, actuated by the drive shaft 14 from any suitable source, a suction is created in the open inlet 8 through which a stream of air is permitted to enter that in passing acts to induce a flow of oil from the feed pipe 10; it being obvious that this oil feed is controlled by a float or other suitable valve as is common practice and old and well known. This fuel comprising oil and air in predetermined quantities is drawn into the pump through the perforations 12 in the liner 11 during which it is partially mixed and atomized due to its heavy impact with the perforated ring.

The rotor vanes 16 held in contact with the liner by the springs 19 maintain an almost fluid tight relation because of the presence of the fuel of high lubricant qualities so that the rotor is exceedingly efficient in operation and the completely atomized fuel is blown out of the outlet 9 at a high velocity where the impact with the perforated liner more thoroughly agitates the mixture.

As is usual in this type of pump there is considerable pressure about the outlet, as the fluid is pumped in this way, and so when approaching the outlet the oil reservoirs 20 are filled with the mixture, which supply they maintain while the rotor is in motion and on its cessation those pockets or reservoirs remaining above the horizontal plane of its axis retain their full complement that tends to condense on the leakage of pressure when the pump is idle. This supply is thus obviously instantly available on the starting of the rotor, acting to immense advantage in providing the initial supply of fuel for ignition and lubricating the liner and vanes whose efficacy is increased by the fluid tight seal resulting between them.

From the foregoing description taken in connection with the accompanying drawings, it will be manifest that a fluid pump is provided which will fulfill all the necessary requirements of such a device, but as many changes could be made in the above

description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

Having thus described my invention what I claim as new and desire to secure by Letters Patent is:—

1. A fluid pump including a stator casing; a rotor mounted eccentrically therein and having equally spaced uniform alternating fluid carrying and vane accommodating radial pockets of uniform capacity; reciprocally operating vanes working in the said vane accommodating pockets and adapted to be changed to the said fluid carrying pockets and thus permitting the vacated pockets to then serve as the fluid carrying pockets; a lining within said casing and provided with spaced perforations opposite the intake and discharge ports of said casing; and a spring for each of said vanes to constantly urge the same into contact with said lining.

2. A fluid pump including a stator casing; a rotor mounted eccentrically therein and having equally spaced identical pockets all of which are of uniform capacity; alternate pockets of said rotor serving as fluid mixing pockets; reciprocating operating vanes working in the remaining pockets between the same pockets serving as fluid mixing pockets; a lining within said casing and provided with spaced perforations opposite the intake and discharge ports of said casing; and a spring for each of said vanes to constantly urge the same into contact with said lining.

In testimony whereof I hereunto affix my signature.
